PAVING STRUCTURE

William C. Burrell, Kankakee, Ill., assignor of
one-half to The Philip Carey Manufacturing
Company, a corporation of Ohio

Application April 14, 1937, Serial No. 136,869

13 Claims. (Cl. 94—18)

This invention relates to paving construction in which a novel and improved expansion joint unit is provided at intervals to divide the paving into spaced apart sections and the spaced apart sections are joined by a jointed load transmitting device, projecting through the expansion joint unit to hold the sections in proper alignment and prevent the adjacent ends being displaced relatively to each other. The invention further relates to a staking means of novel and improved design for securing the expansion joint unit in place upon a suitably prepared foundation over which the concrete slabs are poured in place.

The expansion joint unit may be advantageously formed of complementary sections, preferably of somewhat similar construction and hollowed out, so that when fitted together in the paving structure they will provide a hollow chamber. The staking means is of a construction to prevent any access of foreign material into the chamber of the joint, and particularly to exclude the poured cement from interfering with the operation of the jointed load transmitting devices.

For a better understanding of the invention reference is made to the accompanying drawings, in which:

Fig. 1 is a cross-sectional view of a section of pavement provided with an expansion joint unit embodying the invention;

Fig. 2 is a perspective view of one end of a section comprising the expansion joint unit;

Fig. 3 is a cross-sectional view of a section of pavement provided with the expansion joint unit having the novel and improved load transmitting means projecting therethrough and both staked in position;

Fig. 4 is a top plan view of one of the load transmitting means;

Fig. 5 is a cross-sectional view taken through the overlapped ends of the load transmitting means;

Fig. 6 is a cross-sectional view of a section of the pavement provided with the expansion joint unit having the novel and improved load transmitting means projecting therethrough and both staked in position;

Fig. 7 is a side elevational view of the expansion joint unit and the staking means in place on the foundation with the load transmitting means removed and before the paving sections are poured.

Fig. 8 is a perspective view of the expansion joint unit with the load transmitting means and stakes assembled for insertion in the pavement;

Fig. 9 is a perspective view of one of the staking devices;

Figs. 10 and 11 are perspective views of modifications for staking the expansion joint unit in place; and

Fig. 12 is a plan view of the link provided in Fig. 11 for receiving the stakes.

Referring to the drawings in which like numerals are used to designate like parts, numeral 1 designates a foundation which has been leveled off or otherwise prepared to receive concrete paving applied in sections 2 which are poured in place over the foundation with expansion joint units 3 separating and dividing the sections at spaced intervals. The expansion joint strips are secured in place upon the foundation before the sections 2 are poured around them.

The expansion joint unit is preferably made of any suitable materials. Thermoplastic materials which are readily molded into suitable form and which are plastic or elastic are especially suitable.

20 Rubber and asphalt compositions are particularly suitable. Or the expansion joint unit may be made of more rigid material, such as wood, pulp board, metal or the like which may be treated with a suitable waterproofing material. In order that the expansion joint unit may be light in construction and be readily assembled, it is advantageously made in complementary sections 4 and 5 which may be similar in construction, each being provided with a marginal flange 6 and any number 25 of intermediate projections 7. These intermediate projections may be of any shape or design but are preferably disposed so that they will be formed directly opposite the projections on the other section. The marginal flanges surrounding 30 the sections are preferably continuous so that when they are in abutting relation, with the sides having the projections laid face to face, the interior of the joint unit will have a chambered portion completely sealed by these marginal flanges which prevent any foreign substances 35 such as water or the like gaining access into the chamber of the joint. Substantially the same result could be obtained by having one of the sections constructed as above described and faced 40 with a smooth surfaced closure section. The smooth surfaced closure would seat upon the edge flange and the intermediate projections. The bottom edge of the sectional expansion joint unit may advantageously be provided with a sealing strip 8 of any suitable flexible metal such as copper or the like. This is preferably provided with a beading 9 interposed between corners 10 which are adapted to receive the lower corners of 45 the expansion joint unit and seat it upon the bottom sealing member. Extensions 11 are provided

on the sealing member to project and be embedded into the adjacent ends of the concrete sections.

A crown seal 12 is also provided for the upper edge of the expansion joint unit. This may be of the same type as the bottom seal, or it may advantageously be made in two parts essentially similar in construction with one part attached to one of the expansion joint sections and the other part attached to the other section. Portions 13 of the sealing parts are positioned to overlap with each other, and other parts 14 are provided for anchoring with the paving sections. This top seal may be made of any suitable material, it being preferably formed of the same light flexible metal as the bottom seal. The parts 14 may be reenforced by retroverting the end 15 of the sealing part upon the bent out flange portion 16. An intermediate flange 17 is provided extending upward a short distance from the top edge of the expansion joint section, the flange being disposed parallel with the face of the expansion joint section. These provide suitable edges against which a finishing tool may be operated to smooth off the concrete above the joints. These upper sealing parts may be conveniently attached to the upper edges of the expansion joint sections by any suitable means, such as nails 18, disposed at suitable spaced intervals.

If desired the ends as well as the top and bottom of the expansion joint unit may likewise be sealed with a sealing strip similar to that which is employed on the bottom edge or to that which is applied on the upper edge. The chambered sectional expansion joint structure permits the material, when the sections or one of them are made out of compressible material, to be compressed within the chambered portion, thereby preventing the expansion joint material from being squeezed from the space between the paving sections.

The expansion joint units are preferably installed before the paving is poured, and a suitable staking means 19 may be employed for holding the expansion joint unit in place. A staking means disposed at alternate intervals on each side of the expansion joint unit is preferred. A suitable staking means is typified by an angular member provided with one portion 20 adapted to engage the inner side of one of the sections and another portion 21 disposed to project through a recess 22 provided in the section. A recess 23 may be conveniently provided near the end of portion 21 to receive a staking device 24.

With these expansion joint units, it is desirable to provide load transmitting means for securing the paving sections 2 in alignment and holding the expansion joint unit in place. This means is preferably in the form of channel members 25 and 26 having a back portion 27 and side flanges 28 extending therefrom. The ends of the two sections are overlapped with the side flanges facing each other in overlapping relation and alternately disposed, with a fastening means, such as a bolt 29 inserted for holding the plates in position for handling and properly positioning same in the paving. The bolt is fitted so that the flange 28 of the corresponding sections will be close together and provide only a limited pivotal movement upon the bolt. A filler 30 may be conveniently placed within the space between the overlapping ends, thereby requiring a bolt which is merely heavy enough for holding the overlapping sections together while they are being assembled in position. The jointed structure of

the load transmitting means permits slight pivotal movement of the sections but keeps them in alignment without one paving section being raised above the other. Accordingly, the tendency for the load transmitting devices to shear, as in the case of solid one piece dowels, is overcome. The recesses 29a in the channel sections for receiving the bolts are elongated so that the channel sections may slide relatively to each other.

It is, of course, important that the concrete material should not flow into and fill the space between the overlapped ends of the load transmitting device, particularly where a filler block is not used. It is desirable, too, to exclude the concrete from a space around the overlapped ends, and means may be conveniently associated with the staking means 19 for this purpose. Metal means 32 may be formed with a lower blade portion 33 adapted to be driven into the foundation. The upper portion is formed into a box-like structure 34 having end walls 35 and 36, the latter having a tapered extension 37 that may be driven into the side of the expansion joint unit for holding the stake in place. Portions 38 and 39 are bent to provide side walls for the box-like structure, these being of the same height as the end walls exclusive of the tapered portion 37. One side of the box-like structure is recessed at 49, cut in the form of a U to conform to the contour of the channel members in order that the stakes may be readily slipped over the ends of the channel members and pressed against the expansion joint unit with the tapered portion 37 biting therein. The staking means not only functions to secure the expansion joint unit and the load transmitting device in position but also to exclude any material flowing into the chamber within the expansion joint unit and into the chamber or space between the overlapping end of the load transmitting sections.

In Fig. 10 there is disclosed a modified form of the staking device illustrated in Figs. 3, 6, 7, 8, 9 and 10. The box-like structure for fitting over the end of the load transmitting device is the same. However, in lieu of the blade 33, side walls 38 and 39 may be provided with a fin 41 having the ends 42 disposed at a suitable angle thereto for receiving a stake 43 projected through recesses 44 provided in the ends 42.

Figs. 11 and 12 disclose another staking construction, this being particularly suitable for being driven through the expansion joint unit without any holes being first formed. The staking device is in the form of a clip 45 having one or both ends tapered at 46. Recesses 47 are provided in the ends of the clip sufficiently spaced apart so that stakes 48 may be driven therethrough on either side of the expansion joint unit.

While I have illustrated several embodiments of the invention and described same in detail, it will be understood that there may be various changes and modifications within the scope of the invention and the appended claims.

I claim:

1. A load transmitting means comprising a plurality of U-shaped channel members pivotally connected with the channels of said members facing toward each other and the side flanges of the sections in overlapping relation and alternately disposed.

2. A load transmitting means comprising a plurality of pivotally connected U-shaped channel members disposed in end to end overlapping relation with the channels of said members fac-

ing toward each other and the side flanges of the U sections in overlapping relation and alternately disposed.

3. In a paving construction composed of spaced apart paving sections, an expansion joint strip interposed between the sections, pivotally connected channel sections projected through the joint strip and embedded in the ends of adjacent paving sections, and means provided adjacent the strip to space the paving sections from a portion of the channel sections.

4. In a paving construction composed of spaced apart paving sections, an expansion joint strip interposed between the sections, pivotally connected channel sections projecting through the joint strip and embedded in the ends of adjacent paving sections, and a box-like means fitted over the end of the channel sections to abut the joint strip and space the paving sections from a portion of the channel sections.

5. A load transmitting means comprising a plurality of pivotally connected members, one member being an angle bar and the other member being pivoted thereto and disposed in relation to a side of the angle bar for limiting the relative pivotal movement of the two members.

6. A load transmitting means comprising a plurality of pivotally connected members, one member being an angle bar and the other member being pivoted thereto and disposed in relation to a side of the angle bar for limiting the relative pivotal movement of the two members, and covering means having a recess of a contour to receive the members.

7. In combination with a joint strip and a sectional load transmitting means having the sections connected together and projecting through the joint strip, a covering means covering the connection between the sectional members of the load transmitting device, and stake receiving means on the covering means.

8. A load transmitting means comprising a plurality of members disposed with adjacent ends in overlapping relation, the end of one member being in the form of a U-shaped channel and an end of the adjacent member disposed within the U-shaped channel between the side flanges of the U-shaped member.

9. A load transmitting means comprising a plurality of U-shaped channel members disposed in end to end overlapping relation with the channels facing toward each other and with the respective opposite side flanges of the U-shaped members arranged sufficiently close together to limit relative angular movement of the members.

10. A load transmitting means comprising a plurality of overlapping members disposed to permit relative angular movement to each other, one member being a bar with spaced apart flanges disposed at an angle to a base portion to provide a socket and the other member having an end portion projecting into the socket, a loose connection for holding the overlapped portions together and permitting limited relative pivotal and slidable movement of the projecting end of one member between the spaced apart angle flanges of the other member.

11. A load transmitting means for joints in concrete paving comprising a plurality of sections slidably and pivotally connected together by means of openings in the adjacent ends of the sections and a pin projecting in said openings, the opening in at least one of the sections being greater than the cross section of the pin to provide relative slidable movement, and means on one section defining a range of movement for limiting the pivotal movement of the sections.

12. A load transmitting means for joints in concrete paving comprising a plurality of sections, one of which sections has a socket for receiving the end of another section, a pin and slot for pivotally and slidably connecting the sections together, and means for limiting the relative pivotal and slidable movement of the sections.

13. A load transmitting means for joints in concrete paving comprising a plurality of sections, one of which has a socket for receiving the end portions of another section, pin means for pivotally connecting the sections together, and an elongated slot provided to receive the pin connection to permit the sections to slide relatively to each other, and the walls of the socket disposed to limit the relative pivotal movement of the sections.

WILLIAM C. BURRELL.
